UNITED STATES PATENT OFFICE.

THOMAS BENNINGFIELD, OF ALVA, OKLAHOMA.

DEVICE TO FACILITATE THE TEACHING OF SIGHT-READING.

1,278,425.

Specification of Letters Patent. Patented Sept. 10, 1918.

Application filed March 27, 1916. Serial No. 87,068.

To all whom it may concern:

Be it known that I, THOMAS BENNINGFIELD, a citizen of the United States, residing at Alva, in the county of Woods and 5 State of Oklahoma, have invented certain new and useful Improvements in Devices to Facilitate the Teaching of Sight-Reading, of which the following is a specification.

10 This invention relates to a device to facilitate the teaching of sight reading, rapid calculation and otherwise assisting in the instruction of the student.

Another object of the invention is to provide means whereby a teacher may instantly throw into view a series of figures, letters, or other objects intended for the purpose of instruction.

With the above and other objects in view 20 which will later on be more fully explained I have invented the device illustrated in the accompanying drawings, in which

Figure 1 is an elevational view of my device,

25 Fig. 2 is a sectional view taken on line 2—2 Fig. 1,

Fig. 3 is a sectional view taken on line 3—3 Fig. 2,

Fig. 4 is an enlarged detail view of a key 30 operated mechanism,

Fig. 5 is a sectional view taken on line A—A Fig. 8 showing a card attached to a support therein,

Fig. 6 is a similar view taken on line 35 B—B Fig. 8,

Fig. 7 is an elevational view of a card having a character printed thereon, and

Fig. 8 is a detail elevational sectional view of a card support and operating mechanism therefor, the latter being partly broken away.

Like reference characters indicate like parts throughout the specification and in the several views of the drawings, in which 45 1 indicates a casing having a horizontal fulcrum bar 2 to which is pivoted a series of any desired number of levers 3 and 4, the levers 3 terminating in white operating keys 5 and the levers 4 terminating in black 50 operating keys 6 on a plane higher than the said white keys. On the rear wall 7 of the said casing 1 is a bar 8 which forms a rest

10 for the rear ends 9 and 11 of said levers 3 and 4. A felt or other cushion 12 is mounted on said bar 8 to prevent noise 55 caused by the contact of said levers and bar.

Hingedly mounted on to said bar 8 is a spring supporting member 13 which carries a spring 14, for each of, and directly opposing said rear ends 9 and 11 of said levers 60 3 and 4. The lower vertical ends 15 of said springs are fixed to said member 13 and the upper horizontal portions 16 thereof project slidably through the openings 17 in said member 13. When raised said 65 ends 9 and 11 are adapted to press against the inclined portions 18 of said springs 14 until said ends are permitted to pass from engagement with said springs whereupon said springs fly back to their normal position, and under said ends, whereupon said 70 ends are held raised until by a rearward movement of the rod 19, which is connected to said hinged member 13, all of said springs 14 are thrown out of engagement 75 with all of said lever ends whereby they are permitted to drop back to their normal horizontal positions. By drawing the rod 19 forward the springs are again set to operative position.

Upon the rear portion of each of said levers 3 and 4 are pivotally mounted uprights 20 and 21 connected thereto by links 22 pivoted to said levers at 23 and to said uprights 20 and 21 at 24 whereby said uprights project through openings 25 and 26 in the bottom wall 27 of the upright casing 28. The members 20 and 21 have cut-out portions 29 providing walls 30 against which the character bearing cards 31 are 85 held by means of the spring clips 32, said cards having cut-out portions 33 whereby they straddle said members 21 and are held in rigid vertical position. A spring 34 holds the rod 19 in any shifted position. 90

The case 28 is provided with glass front and back walls 36 and 35 whereby the characters 37 on the cards 31 may be exposed to view from either front or rear of the device in order that the teacher operating the 100 device may see the letters, words, figures, or other characters on the raised leaves as well as the students.

The character bearing upright rods may

be arranged in one row or a plurality of rows and the rods in one row may be of a different length than the rods in another row so that two or more lines of reading 5 may be exposed in the casing 28.

A drawer 38 is provided in the case 1 to hold character bearing cards of a large variety so that the study to be given on the device may be changed or arranged at will 10 by the teacher. 39 is a counting device having rows of counters 40 and 41 strung upon wires 42 and 43.

Having now described my invention that which I claim to be new and desire to procure by Letters Patent is:—

1. The described device consisting of a series of levers, character cards carried by said levers, and means for engaging the rear ends of said levers to hold them raised.

2. The described device consisting of a series of levers, character cards carried by said levers, means for engaging the rear ends of said levers to hold them raised, and said means consisting of springs.

3. The described device consisting of a series of levers, character cards carried by said levers, means for engaging the rear ends of said levers to hold them raised, said means consisting of springs, and a bar upon 30 which all of said springs are mounted.

4. The described device consisting of a series of levers, character cards carried by said levers, means for engaging the rear ends of said levers to hold them raised, said 35 means consisting of springs, a bar upon which all of said springs are mounted, and said bar being horizontally disposed.

5. The described device consisting of a series of levers, character cards carried by 40 said levers, means for engaging the rear ends of said levers to hold them raised, said means consisting of springs, a bar upon which all of said springs are mounted, said bar being horizontally disposed, and hing- 45 edly mounted.

6. The described device consisting of a series of levers, character cards carried by said levers, means for engaging the rear ends of said levers to hold them raised, said 50 means consisting of springs, a bar upon which all of said springs are mounted, said bar being horizontally disposed and hing- edly mounted, and means for operating said bar on said hinges.

7. The described device consisting of a series of levers, character cards carried by said levers, means for engaging the rear ends of said levers to hold them raised, said 55 means consisting of springs, a bar upon which all of said springs are mounted, said bar being horizontally disposed and hing- edly mounted, means for operating said bar on said hinges to trip said raised lever ends.

8. The described device consisting of a 65 series of levers, character cards carried by said levers, means for engaging the rear ends of said levers to hold them raised, said means consisting of springs, a bar upon which all of said springs are mounted, said bar being 70 horizontally disposed and hingedly mounted, means for operating said bar on said hinges to trip said raised lever ends, and holders for each of said cards.

9. The described device consisting of a 75 series of levers, character cards carried by said levers, means for engaging the rear ends of said levers to hold them raised, said means consisting of springs, a bar upon which all of said springs are mounted, said bar being 80 horizontally disposed and hingedly mounted, means for operating said bar on said hinges to trip said raised lever ends, holders for each of said cards, and said holders being carried by said levers.

10. The described device consisting of a series of levers, character cards carried by said levers, means for engaging the rear ends of said levers to hold them raised, said means consisting of springs, a bar upon 85 which all of said springs are mounted, said bar being horizontally disposed and hing- edly mounted, means for operating said bar on said hinges to trip said raised lever ends, holders for each of said cards, said 90 holders being carried by said levers, and pivotally connected therewith.

11. The described device consisting of a series of levers, character cards carried by said levers, means for engaging the rear ends of said levers to hold them raised, said means consisting of springs, a bar upon 100 which all of said springs are mounted, said bar being horizontally disposed and hing- edly mounted, means for operating said bar on said hinges to trip said raised lever ends, holders for each of said cards, said 105 holders being carried by said levers and pivotally connected therewith, and a cushion to receive said lever ends when dropped.

12. In the described device, a series of hidden lettered cards, means for independently raising said cards, and a hinged bar whereby said cards may be simultaneously 110 dropped from view.

13. An indicating device comprising a sectional casing, transverse supporting bars connected to one of the sections of said casing, a hinged member attached on one of the said transverse bars, an operating device connected to said hinged member, vertical bars supporting indicating devices, and means upon said hinged member to lock said vertical supporting bars in elevated position, said last mentioned locking means being released upon the operation of said first mentioned locking means.

14. An educational device comprising

means to elevate educational characters, hinged means to retain said educational characters in elevated position, means to release said retaining means, and means to 5 lock said retaining means against movement upon its hinges.

15. An educational device, comprising operating means, supporting means, indicating means mounted in said supporting 10 means, having like indications upon the opposite faces thereof, hinged means to lock said supporting means in an elevated position and means to release said locking means.
- 15 16. An educational device comprising a plurality of pivoted operating devices, a plurality of supporting devices connected to said operating devices, a plurality of double faced indicating devices mounted in said 20 supporting devices, a hinged device having

a plurality of locking means to lock said supporting devices in an elevated position, and means to release said locking means.

17. An educational device comprising a casing, double faced indicating devices 25 housed in said casing, operating means to elevate said indicating devices into view, a pivoted device supporting a plurality of locking means, said locking means being flexible against action in one direction and 30 inflexible against action in the opposite direction, and means to shift said locking means out of operative position.

In testimony whereof I affix my signature in the presence of two witnesses.

THOMAS BENNINGFIELD.
